LIGHTING DEVICE

Hans J. Spanner, Berlin, Germany, and Ulrich Doering, New York, N. Y., assignors, by mesne assignments, to said Hans J. Spanner

Application April 30, 1929, Serial No. 359,329, and in Germany September 21, 1928

3 Claims. (Cl. 176—122)

This invention relates to gas discharge devices, particularly to tubes that are used for lighting purposes and are operated directly from an ordinary low voltage supply circuit. One of the difficulties commonly experienced with such devices is in igniting them, that is, in starting the discharge between the electrodes which are spaced a considerable distance apart. It is one of the objects of the present invention to provide improved means for starting or igniting such lighting devices which shall be simple in construction and operation, dependable in action, and not likely to get out of order.

In order to more clearly explain the invention, reference is made to the following description of different embodiments thereof taken in connection with the following drawing, in which

Fig. 1 is a longitudinal section of a gas discharge device, the external connections being shown in diagrammatic form;

Fig. 2 is a longitudinal section of another form of gas discharge device; and

Fig. 3 is a longitudinal section of still another form of a gas discharge device.

The reference character 11 indicates a glass container or tube having electrodes 12 and 13 positioned in each end thereof. The electrode 12 may be in the form of a helix of wire having an emitting coating and may be provided with leading-in wires 14 and 15. The electrode 13 may be of similar construction and may be provided with leading-in wires 16 and 17. Suitable means may be provided for furnishing a conductive path from one end of the tube to the other, such as a wire helix 18, which has leading-in wires 19 and 20 at the respective ends thereof. The leading-in wires 14 and 19 are connected together and to a conductor 21 which is connected to some suitable source of supply not shown, and in which

there is connected a current limiting impedance 22. The leading-in wires 17 and 20 are also connected together and to a conductor 23 which is connected to the other side of the source of supply from that to which the conductor 21 is connected. A suitable auto transformer 24 may be connected between the conductors 21 and 23 and conductors 25 and 26 are connected from intermediate points of the winding of the auto transformer and are used for supplying current to the leading-in wires 15 and 16 of the electrodes 12 and 13. The resistance of the helix 18 may be so chosen that the current flowing therethrough is only a small fraction of the current employed for the operation of the gaseous discharge path and the energy consumed therein is relatively

small. The material used for the filament or helix 18 is preferably of such a character that it will not be readily disintegrated by ionic bombardment, examples of such material being tungsten wire coated with aluminum or beryllium or compounds thereof. It is also desirable that the conductive connection between the two ends of the tube should be emissive and for this purpose a coating may be provided of one of the strong electropositive metals such as of the alkali or alkali-earth groups or compounds thereof. It has been found possible to employ such highly active metals as caesium, rubidium, potassium and barium. The connecting filament may also be activated by loading it with hydrogen. Such coatings may have associated therewith an amphoteric oxide such as aluminum oxide or zirconium oxide which renders such emissive substances highly resistive to ionic bombardment or disintegration.

In operation, the current flows through each of the electrodes 12 and 13 heating them and producing an electronic emission. The relatively low supply voltage of 110 volts or 220 volts, however, does not readily start the discharge between the two electrodes. But as the emissive material on the helix 18 is heated and the emission along this conductive path is produced the discharge is readily started between one of the electrodes and the adjacent portion of the helix 18 and thereafter the discharge extends throughout the entire length of the tube.

In the form shown in Fig. 2 the conductive connection between the two ends of the tube is in the form of a metallic strip folded or bent in a zig-zag form and preferably touching the tube 11 at only a few points as 31 and 32. The external connections and other details of construction may be as shown in Fig. 1.

In Fig. 3 a glass container or tube 11a may be provided with bends 11b and 11c and laterally extending end portions 11d and 11e in which are positioned the electrodes 12 and 13. The conductive connection between the two ends of the tube may comprise a middle portion 18a bent in a zig-zag form and end portions 18b and 18c in the form of helixes so that the potential drop near the ends of the tube is much greater than in the middle of the conductive connection and more nearly corresponds with the drop of potential throughout the gaseous discharge path during stable operation of the tube. The portion 18a is preferably supported at relatively few parts of the tube as at 18d and 18e near the bends of the tube. By thus increasing the potential drop of

the filament near the ends of the tube it is possible to start an arc more readily near the electrodes because of the shorter distance over which the potential drop to the filament is concentrated.

- 5 In the foregoing description the conductive connection is a metallic filament or wire but it may also be in the form of a metallic strip or deposit on the walls of the glass. In place of emissive coatings on the filament which carries
 10 the heating current, separate bodies may be provided for the emissive coatings. Also the heating may be by means of the action of the gaseous discharge itself on the electrodes. In providing the conductive connection between the electrodes
 15 with emissive material and in heating it, it may not be necessary to bring about emissivity of electrons in the ordinary meaning of the word, as it may be sufficient to raise the temperature sufficiently to increase the electron density at the
 20 surface to a suitable degree when the molecules which strike the surface of the conductive connection will become charged by virtue of a clinging electron or electrons. Also the ions which are driven against the surface set free secondary
 25 electrons if the velocity of the ions is sufficiently high, say corresponding to 10 to 20 volts. As a practical matter, the main discharge usually

takes place before the conductive connection comes to a red glow.

We claim:

1. A gas discharge device comprising a container, a plurality of electrodes positioned therein, and a thin strip of electrically conductive material connecting said electrodes, said conductive material being in the spiral form adjacent to the electrodes and having a zig-zag form at points intermediate said spiral form whereby said strip is supported at relatively few points against the sides of the container. 80

2. A gas discharge device comprising a container, a plurality of thermionic electrodes positioned therein and a thin strip of electrically conductive material connecting said electrodes, the surface of said strip comprising a highly emissive oxide of alkali earth. 90

3. A gas discharge device comprising a container, a plurality of electrodes positioned therein, and a thin strip of electrically conductive material connecting said electrodes, the resistance of said strip being of a higher order near at least one electrode than on the rest of its length. 95
